DESIGN FOR A BOTTLE

Walter C. Ross, New York, N. Y.

Application September 24, 1935, Serial No. 58,683

Term of patent 7 years

To all whom it may concern:

Be it known that I, Walter C. Ross, a citizen of the United States, residing at 405 East 54th St., New York, in the county of New York and State of New York, have invented a new, original, and ornamental Design for Bottles, of which the following is a specification, reference being had to the accompanying drawing, forming a part thereof, and in which

Fig. 1 is a side view; and
Fig. 2 is a top plan view of a bottle showing my design.

I claim:
The ornamental design for a bottle, as shown.

WALTER C. ROSS.
